RELEASING AND HOLDING MEANS FOR
RAILWAY CAR HAND BRAKES

Richard W. Burnett, Chicago, Ill.

Original application May 28, 1928, Serial No.
281,088. Divided and this application Feb-
ruary 27, 1930, Serial No. 431,763

7 Claims. (Cl. 188—81.1)

This invention relates to railway car hand brakes and particularly to improvements in means for holding the hand brake mechanism in and releasing it from its brake setting position.

The primary object of the invention is to provide an improved releasing and holding means for the hand power mechanism of a railway car hand brake which will be relatively simple in its operation although effective in its results, and which will permit the brakes to be wholly or partially released under the control of the brakeman from a position remote from the hand power mechanism. In this connection the invention contemplates an operating lever for releasing the holding means which may be operated by the brakeman from a position on the ground or on the lower portion of the car but at the same time will permit the holding member to be re-engaged intermittently with the power mechanism to effect a notching off or gradual release of the brakes.

A further object is to provide in a hand brake of the above character means which in combination with the releasing lever, may be positioned to lift the holding member out of its holding position when the releasing lever is actuated and which also may be employed not only to lift the holding member out of its holding position but to apply a retarding pressure to a moving part of the power mechanism.

A further object is to provide a holding and releasing mechanism which in addition to providing automatic means for supporting the holding member out of its holding position provides also an operating lever having a cam portion for engagement with the end of the holding member and adapted upon being swung to either side of the vertical axis of the operating lever to lift the holding member out of its holding position.

This application is a division of my copending application Serial No. 281,088 filed May 28, 1928 (Patent 1,939,953 dated December 19, 1933).

The invention is illustrated in one specific embodiment in the accompanying drawing wherein:

Fig. 1 is a front elevation of a railway car hand brake power mechanism with parts broken away and illustrating my improved holding and releasing mechanism in its normal position for operation.

Fig. 2 is a similar view of the mechanism shown in Fig. 1 but illustrating the parts of the power mechanism and the holding and releasing mechanism in different positions, and

Fig. 3 is a fragmentary plan view of the mecha-

nism as shown in Fig. 1 illustrating the parts in the same relative positions as indicated in that figure.

The hand power mechanism illustrated herein is of a type in which a chain or other suitable connector is wound about a drum, the latter being rotated by means of intermeshing gears operatively connected to a hand wheel. In the particular embodiment illustrated a chain 10 is attached at one end to an arm 11 of a winding drum 12 and is attached at its other end to any suitable means for transmitting the power to the brake rigging underneath the car. The winding drum 12 is preferably provided with a grooved winding surface 13 of eccentric configuration and is so secured to a shaft 14 that the initial turning movement of the drum effects a quick take-up of the slack in the connector 10 and various parts of the brake rigging and further movement winds the chain about a relatively small radius so as to apply maximum power after the brake shoes of the brake rigging have been moved into engagement with the wheels of the car. The diameter of the drum 12 is preferably such that the brake of any normal installation will be fully applied before the drum 12 has made one complete revolution. The shaft 14 is suitably journaled in the front and back portions of a housing 15. The numeral 16 designates a large gear rigidly connected with the drum 12 so as to rotate therewith and meshes with the pinion 17 fixed on a horizontal shaft 18 in the upper portion of the housing. The shaft 18 extends out of the front portion of the housing and carries a hand wheel 19 of suitable diameter for imparting the rotational movement to the winding drum.

It will be seen that by rotating the hand wheel 19 in a clockwise direction with reference to Fig. 1, rotation is imparted to the winding drum 12 in the direction indicated by the arrow so as to wind the chain upon the drum in the manner indicated in Fig. 2. In order to avoid reverse movement of the hand wheel during the brake setting operation and to also provide for releasing the hand brake from its brake setting position, I have provided my improved holding and releasing mechanism. The specific construction of this mechanism illustrated herein consists preferably of a ratchet wheel 20 secured to the shaft 18 in a position between the hand wheel 19 and the front face of the housing 15. A holding member, preferably a pivoted pawl 21 is pivoted to the housing at 22. The under portion of the pawl 21 is provided with a tooth 23 for engagement with the teeth of the ratchet wheel and

is formed also with an arcuate portion 24 which extends over the ratchet wheel and terminates in a foot portion 25. A releasing lever 26 is pivoted at 27 to the housing and is formed with 5 an enlargement 28 which provides a stop for the foot 25 of the pawl and serves also as a cam for raising the pawl 21 out of its holding position. The cam 28 preferably extends on both sides of the vertical center of the axis 27 so that 10 movement of the rod 26 to either side of the vertical center will serve to raise the pawl 21 out of its holding position. The releasing lever 26 may be of any suitable length, preferably it extends downwardly a distance sufficient to permit 15 operation by a brakeman while the latter is standing on the ground. The fact that the releasing lever 26 may be operated by movement in either direction makes it possible for the brakeman, when standing on the car, to release the brakes by using his foot to operate the lever 26.

The pawl member 21 is formed also with a tail portion 29 adapted to engage the ratchet wheel to limit the swinging movement of the pawl and also to provide means for exerting frictional retarding force on the ratchet wheel so as to control 20 the reverse spinning movement of the hand wheel and winding mechanism during the brake releasing operation. In this connection I have provided a second releasing lever 30 pivoted preferably on the same axis as the pawl 21. The lever 30 is provided with a boss 31 adapted, when the lever is in the position illustrated in Fig. 1 to bear upon the upper portion of the pawl 21 so as to maintain it in its ratchet engaging position and which when the lever 30 is moved to the position indicated in Fig. 2 will bear against a shoulder 31^a of the pawl so that the lever 30 will serve as a counter weight tending to raise the pawl out of engagement with the ratchet when the 25 braking pressure on the ratchet is released either by rotation of the hand wheel in a direction to set the brakes or by manipulation of the releasing lever 26. When the lever 30 is in the position indicated in Fig. 2, the reverse spinning movement of the winding mechanism may be retarded by exerting pressure downwardly on the lever thereby forcing the tail-piece 29 of the pawl into frictional engagement with the ratchet wheel. The lever 30 may also be used to release the pawl independently of the operation of the lever 26.

Operation of the holding and releasing mechanism.—Assuming that the brakes are fully set with the holding pawl in a position to prevent reverse movement of the winding drum the pawl 55 may be lifted out of its holding position by movement of the releasing lever 26 to either side of its vertical axis. If it is desired to effect a step by step release the holding pawl 21 may be permitted to reengage with the ratchet gear 60 by a return movement of the lever 26 to its normal vertical position whereupon the weight of the pawl together with the additional weight of the lever 30 will cause the pawl to reengage the ratchet. If it is desired to effect an instantaneous release the lever 30 may be moved to the position indicated in Fig. 2 whereupon a single operating movement of the lever 26 will disengage the pawl and ratchet so that the weight of the lever 30 will support the pawl out of engagement with the ratchet. The same result can be obtained, for example when a graduated release is desired through manipulation of the hand wheel, by rotating the hand wheel in a direction to release the braking pressure from 75 the tooth 23 of the pawl whereupon the weight

of the lever 30 will lift the pawl and support it in the position indicated in Fig. 2. The release of the brakes may then be controlled by the manipulation of the hand wheel 19 or if desired by the downward pressure on the lever 30 so as to force the tail portion 29 of the pawl into frictional engagement with the ratchet. The lever 30 may be used independently of the lever 26 for lifting the pawl 21 out of its holding position when the braking pressure on the pawl is such as not to require compound leverage to effect said release.

While I have illustrated my invention in connection with one specific embodiment, it will be obvious to persons familiar with this art that various modifications may be made in structure without departure from the spirit of the invention. It will therefore be understood that my invention contemplates all such modifications coming within the scope of the appended claims. I do not claim herein the holding and releasing mechanism in combination with the vertically arranged hand wheel as said combination is claimed in my said copending application Serial No. 281,088, (Patent 1,939,953, dated December 19, 1933).

I claim:

1. Holding and releasing mechanism for railway car hand brakes comprising a ratchet wheel, a pawl pivoted to engage the ratchet wheel to hold it against movement in one direction and formed at one end with an extension terminating in a foot and at the other end with a tail-piece adapted to be moved into engagement with the ratchet when the pawl is moved to its ratchet releasing position, an operating lever pivoted near its upper end and formed with a cam operable by a brakeman standing on the ground, to lift the pawl out of its holding position, a holding and tripping device pivoted on the same axis as the pawl adapted in one position to bear against the pawl to maintain it in its holding position and in another position to bear against the tail portion of the pawl to support the pawl in its released position.

2. Holding and releasing mechanism for railway car hand brakes comprising a ratchet wheel, a pawl pivoted to engage the ratchet wheel to hold it against movement in one direction formed at one end with an extension terminating in a foot-piece and formed at the other end with a tail adapted to be moved into engagement with said ratchet when the pawl is moved to its ratchet releasing position, a normally vertically disposed operating rod formed with a cam portion for engagement with said foot-piece of the pawl and adapted upon swinging movement of the lever to either side of its vertical axis to lift the pawl out of its holding position and a second releasing lever pivoted about the same axis as the pawl and adapted in one position of the lever to bear upon the upper portion of the pawl to maintain it in engagement with the ratchet and in another position to support the pawl out of its holding position during the releasing operation of the hand brake.

3. Holding and releasing mechanism for railway car hand brakes comprising a ratchet wheel rotatable about a horizontal axis, a pawl pivoted to engage said ratchet to hold it against reverse movement and formed at one end with a tail-piece and means for releasing the hand brake under control of the operator comprising a lever pivoted on the same axis as the pawl for lifting the pawl out of its holding position and adapted

upon continuous movement thereof to force the said tail portion of the pawl into frictional engagement with said ratchet.

4. Holding and releasing mechanism for a railway car brake comprising a ratchet, a pawl for holding the ratchet against reverse movement when the brakes are in set position, a lever for forcing the pawl from engagement with the ratchet against braking pressure between said elements, and a lever which in one position tends to establish and maintain engagement between the pawl and ratchet and in another position to lift and hold the pawl out of its ratchet holding position when the said braking pressure between the pawl and ratchet is relieved.

5. Holding and releasing means for a railway car brake comprising a ratchet, a pawl for holding the ratchet against reverse movement when the brakes are in set position, a lever provided with a cam to bear against said pawl for disengaging the same from the ratchet, and a member which in one position tends to establish and maintain engagement between the pawl and ratchet and in another position to automatically lift and hold the pawl in a position free of the ratchet upon release of the braking pressure on said pawl.

6. Holding and releasing mechanism for a railway car brake comprising a ratchet, a pivoted pawl for holding the ratchet against reverse movement when the brakes are in set position, a lever pivoted on a different axis from the pawl engageable therewith to disengage the ratchet from the pawl, and a member which in one position tends to establish and maintain engagement between the pawl and ratchet and in another position to lift and hold the pawl out of its ratchet holding position when the braking pressure between the pawl and ratchet is relieved.

7. Holding and releasing mechanism for a railway car brake comprising a ratchet, a pawl for holding the ratchet against reverse movement when the brakes are in set position, an operating rod pivoted to hang in a vertical position and provided with a cam adapted to bear against the pawl and to disengage it from the ratchet when the rod is turned to an oblique position, and a member which in one position tends to establish and maintain engagement between the pawl and ratchet and in another position to lift and hold the pawl to a position free of the ratchet when the braking pressure between the pawl and ratchet is relieved.

RICHARD W. BURNETT.
